UNITED STATES PATENT OFFICE

145,916

DESIGN FOR AN AIRPLANE

Daniel M. Zabiak, Chicago, Ill.

Application October 23, 1945, Serial No. 123,117

Term of patent 7 years

(Cl. D71—1)

To all whom it may concern:

Be it known that I, Daniel M. Zabiak, a citizen of the United States, residing at Chicago, in the county of Cook and State of Illinois, have invented a new, original, and ornamental Design for an Airplane, of which the following is a specification, reference being had to the accompanying drawing, forming a part thereof.

Figure 1 is a top plan view of an airplane showing my new design;

Figure 2 is a side elevational view thereof;

Figure 3 is a front elevational view of same; and

Figure 4 is a transverse sectional view looking to the rear and taken on the line 4—4 of Figure 1.

The appearance of the opposite side of airplane is the same as illustrated.

I claim:

The ornamental design for an airplane, as shown and described.

DANIEL M. ZABIAK.
